TWO STEP LADDER LEG EXTENSION

Perry Demas and Dominic Patsy Bonacci,
Mamaroneck, N. Y.

Application February 8, 1951, Serial No. 210,028

1 Claim. (Cl. 228—63)

1

This invention relates to a two step ladder leg extension and has for an object to provide a leg extension arranged to be attached to the leg of a ladder and when attached is capable of adjustment to any of three positions, a position leaving the ladder leg at its original length, so that the ladder may be used in the ordinary manner, a position extending the length of the ladder leg by one step, particularly intended where the ladder is to be used on a stairway where either the steps are sufficiently wide or where one leg of the ladder is to be placed on the first step of the stairway, and the other leg on the floor at the bottom of the stairway, and a third position wherein the steps of the stairway are fairly narrow and the width of the ladder is such that it stands two steps, whereby the ladder may be placed anywhere along the stairway with two steps intervening between the legs of the ladder.

A further object of this invention is to provide a two step ladder leg extension which may be readily attached to any existing ladder and when so attached will still permit the ladder to be used in its ordinary manner or to be adjusted for either one or two step extensions as may be needed.

Yet a further object of this invention is to provide a two step ladder leg extension wherein there are but two leg parts in the extension, and wherein the two leg parts are locked to each other in either position at three different points and wherein the extension as a whole is locked to the ladder leg likewise at three different points at all times irrespective of whether the extension is in fully retracted position, intermediate position, or fully extended position.

Still a further object of this invention is to provide a two step ladder leg extension which is very simple in construction and operation and wherein the extension legs may be made of wood or suitable light weight metal, such as magnesium, aluminum or the like and may be readily attached to the leg of an existing ladder by merely boring three suitably spaced transverse holes through the ladder leg to which it is to be attached.

A further object of this invention is to provide a ladder leg extension which may be made in either left leg or right leg position, but inasmuch as it has been observed that most stairways require left leg extensions, a left leg extension is herein illustrated.

With the foregoing and other objects in view, this invention comprises the combination, construction and arrangement of parts hereinafter

2

set forth, claimed and disclosed in the accompanying drawings, wherein:

Fig. 1 is a perspective view of the ladder leg extension of this invention attached to a ladder and arranged in the intermediate position and providing a one step extension;

Fig. 2 is a similar view of the extension in the fully extended position providing a two step extension;

10 Fig. 3 is a plan view of the ladder leg extension mounted on a ladder leg in fully retracted position;

Fig. 4 is an edge view of Fig. 3, but in fragmentary sections to show the operating elements, 15 and

Figs. 5, 6, 7 and 8 are sectional views on lines 5:5, 6:6, 7:7 and 8:8 of Fig. 4.

There is shown at 10 a ladder of the conventional type used when papering and painting the 20 walls of a home or building. However, when painting or papering the wall along a staircase, it is usually necessary to use dangerous improvisations, such as a box or the like, under one leg of the ladder so that the ladder can be used

25 on the steps of the staircase. With this invention such conventional ladder 10 may have a ladder leg extension 11 attached to one leg thereof, as the left leg 12, for instance, whereby the ladder 10 may still be used on the walls of any 30 room and may be readily and quickly converted for use on a staircase, irrespective of whether the staircase has wide or narrow steps, and irrespective of whether the ladder itself has wide or narrow steps, it being possible with this invention to

35 so extend the left leg 12 of the ladder 10 that the right leg 13 may be placed one step above the bottom of the extended left leg 12 as shown in Fig. 1, or may be placed two steps above the bottom of the extended leg 12 as shown in Fig. 2. Inasmuch as most staircases 14 usually have the 40 wall located at the left end thereof, the ladder leg extension 11 of this invention has been illustrated for use on a left leg, but it may easily be manufactured suitable for a right leg of a ladder by merely shaping it and placing the parts in mirror image relation to the left ladder leg extension shown herein.

The ladder leg extension 11 of this invention 45 comprises a long extension section 15 and a short extension section 16. The two extension sections 15 and 16 are pivotally bolted together by a bolt 17 having its bolt head 18 countersunk within the outer surface of extension section 15, a nut 20 securing the bolt in position. The bolt head 18 is countersunk in that surface of the leg ex-

50 55

tension 15 which is to be attached to the side of ladder leg 12 by means of a similar pivotal bolt 21, nut 22, and bolt head 23, the bolt head 23 being countersunk in the opposite surface of the leg section 15, that surface which is away from the side of the ladder leg 12 and is in contact with the near surface of the extension section 16. When attaching the ladder leg extension 11 of this invention to a ladder leg 12 three suitably spaced bolt holes must be drilled through the ladder leg, one bolt hole being provided to receive the bolt 21 and two other suitably spaced bolt holes being provided to receive the shanks of screws 24 as shown in enlarged detail in Fig. 7, it being intended that a paper or cardboard template be provided with the ladder leg extension 11 so as to enable the bolt holes to be properly spaced and located when being drilled by the purchaser of the leg extension.

Each threaded screw 24 has a threaded end arranged to screw into a threaded sleeve 26 suitably secured and positioned in extension section 15. A bushing 27 for each of said two other spaced bolt holes is provided on the inside of a flange plate 28 provided with apertures for receiving securing screws 30 and a central aperture through which the slightly reduced shank of the threader screw 24 may slidably extend, and the central aperture in plate 28 may be threaded to permit the screw threads 25 to pass therethrough but not to slide therethrough, a knurled head 31 being provided on the end of the shank for threading the screw threads into or out of the threaded sleeve 26. It will be noted that the pivoting bolt 21 is exactly equidistant between the thread screw 24 and threaded sleeves 26 so that the leg extension section 15 may be pivoted about the bolt 21 and be secured in either position, thread screw 24 thus being able to be secured in either of the identical threaded sleeves 26. Thus when secured in the position shown in Figs. 3 and 4, the original lengths of the ladder leg 12 will be undisturbed. By unthreading the thread screws 24 by means of their knurled heads 31, the threaded ends may be temporarily withdrawn to within the bushings 27, whereupon the entire ladder leg extension 11 may be pivoted about the bolt 21 as a center for 180° and then the thread screws 24 may be screwed back into the other threaded sleeves 26 which are now in proper position to thus secure the ladder leg extension 11 in the position shown in Fig. 1, thus making the length of ladder leg 12 one staircase step longer than the length of the other leg 13.

To convert the ladder leg extension 11 for use on two steps of the staircase 14, it is first put in position for the one step extension as provided and explained above, then the extension section 16 is pivoted 180° about the pivoting bolt 17. That end of extension section 16 which is closest to the pivot bolt 17 is provided with a somewhat S-shaped hook 32 integrally formed at the end thereof, thus providing two abutment receiving recesses 33 and 34, and the remainder of the end of extension section 16 may be somewhat curved as at 35. An abutment pin 36 is permanently secured as at 37 near the adjacent end and through the extension section 15. Located on a diagonal line through pivot bolt from the recess 33 is a recess 37 on the opposite edge of the extension section 16 so that such recess will have its inner end abut against the pin 36 when rotated 180°. Countersunk within the leg extension 15 is a spring pressed abutment pin 38 secured therewithin in a housing 40 and nor-

mally urged outwardly thereof by the spring 41. This abutment 38 is in such position and location in the leg extension 15 that when the leg extension 16 is pivoted about its pivoting bolt 17 from the position shown in Fig. 1 to the position shown in Fig. 2, the abutment pin 38 will be urged outwardly by spring 41 and held outwardly within housing 40 so that the abutment recess 37 abuts against the fixed abutment pin 35, thus providing three locking points for the leg extension 16 in the two step extension position of Fig. 2.

It will be noted that the supporting end 42 of leg extension 15 and supporting end 43 of leg extension 16 all have the same angle as the supporting end 44 of ladder leg 12 so as to provide the same firm support as originally provided by the ladder leg 12. If the leg extension 11 be manufactured to fit the right hand ladder leg 13, then, of course, the angles at the supporting ends of the leg extensions will be parallel to the angle of the supporting end of leg 13 and the abutment pins and recesses for receiving the abutment pins will be placed in reverse mirror image position.

Due to the fact that the ladder 10 must lean against a wall in position and thus be at an angle, gravity serves to lock leg extension 16 in position on its pivot bolt against the abutment pins in the abutment recesses. To move the leg extension 16 back to the non-supporting position, it is merely pivoted about its bolt 17, the abutment pin 38 being depressed against its spring 41 allowing the extension section 16 to pivot thereover. The friction of the end of abutment pin 38 pressed by spring 41 against the inner surface of extension section 16 should be sufficient to hold extension section 16 in the non-supporting position and to insure this being so held, a slight depression 42' may be provided on the inner surface of leg extension section 16 at the end of the path 43' as shown in Fig. 3 over which the abutment pin 38 travels when extension section 16 is being pivoted thereabout, the recess 42' being connected to path 43' by a slight angle, thus enabling pin 38 to ride in and out of the recess 42' without difficulty.

In operation, the leg extension 11 is secured to the leg 12 of a ladder 10 by providing suitably spaced bolt holes in the ladder leg 12 and securing the screw threads 24 therethrough as above described. Obviously, instead of using the especially convenient screw threads 24 as herein disclosed, suitably countersunk bolts and nuts could be provided, but inasmuch as they would have to be removed during the pivoting operation, such ordinary bolts and nuts are liable to be easily lost. By pivoting extension 11 as a whole about the pivoting bolt 21, the extension 11 of this invention may be shifted between the non-supporting position shown in Figs. 3 and 4 and the one step supporting position shown in Fig. 1. If desired to be used in a two step supporting position as shown in Fig. 2, it is first pivoted to the one step supporting position as above described and shown in Fig. 1, and then leg extension section 16 is further pivoted about the pivoting bolt 17 to bring abutment recesses 33 and 37 into contact with spring pressed abutment pin 38 and fixed abutment pin 36, thus holding the leg extension section 16 in supporting position when the ladder 10 is at an angle as in customary use. To restore it to one step position the leg extension section 16 is merely

reversely pivoted while depressing the abutment pin 38 against the spring to permit the pivoting movement to be completed. Then if desired to restore it to non-supporting position thread screws 24 are withdrawn, the whole extension 11 pivoted and thread screws 24 again threaded in, thus holding the extension 11 on the leg 12 but completely and non-supporting position.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

A ladder leg extension, means for pivotally securing said extension to a ladder leg in adjustable position thereon so that the ladder may be used on a level floor, or be supported on a staircase with either one or two staircase steps between the ladder legs, said ladder leg extension comprising two extension leg sections pivotally secured together, means for pivotally securing and attaching one of said leg sections to a ladder

leg, means for detachably fastening said one leg extension section to the ladder leg at two additional securing points in parallel relation thereto and at either of two positions 180° apart thereon, and means securing said other leg extension section in supporting relation to said one leg extension section and to the ladder leg when both of said sections are pivotally adjusted in extended position, said detachable fastening means comprising a pair of threaded sleeves in said one leg extension section equally spaced in said section on opposite sides of said securing means, and a pair of correspondingly spaced threaded screws extendably and retractably mounted in the ladder leg.
